UNITED STATES PATENT OFFICE.

BENJAMIN F. BADDELEY, OF SAN FRANCISCO, CALIFORNIA, ASSIGNOR OF FORTY-NINE PER CENT TO J. CHARLES KING, OF SAN FRANCISCO, CALIFORNIA.

PADDLE PROPELLER.

Application filed January 2, 1920. Serial No. 348,822.

To all whom it may concern:

Be it known that I, BENJAMIN F. BADDELEY, a citizen of the United States, residing in the city and county of San Francisco and State of California, have invented new and useful Improvements in Paddle Propellers, of which the following is a specification.

This invention relates to a propeller of the paddle type, especially adapted for 10 steamers navigating in shallow rivers, harbors and the like.

One of the objects of the present invention is to provide a propeller of the paddle type adapted for river steamers and the like, 15 and especially to provide means for adjusting the dip of the paddles to permit maximum efficiency of the same whether the steamer is lightly or heavily loaded.

Another object of the invention is to provide 20 a paddle propelling unit consisting of four cranks and two paddles; two cranks for each paddle, and in conjunction therewith means for driving the cranks and paddles in unison and at constant speed.

Another object of the invention is to provide 25 means for vertically adjusting the position of the paddles with relation to their respective cranks.

Further objects will hereinafter appear. 30 The invention consists of the parts and the construction, combination and arrangement of parts as hereinafter more fully described and claimed, having reference to the accompanying drawings, in which—

Fig. 1 is a side elevation of a hull showing the rear end thereof and the position of 35 the paddle propellers.

Fig. 2 is a similar view drawn in an enlarged scale.

Fig. 3 is a plan view of Fig. 2.

Referring to the drawings in detail, A indicates the stern end of a river steamer or the like, and B a rearwardly extending frame consisting of two pair of superimposed interspaced horizontally positioned timbers such as indicated at 2 and 3. These timbers are suitably tied together as at 4 and braced as at 5, and they are in this instance provided for a support for the paddle propellers indicated at 6 and 7. Supported on the timbers 2 are journal members 8, and similarly supported and secured on the lower timbers 3 of the frame B are journal members 9, the journals 8 and 9 on 55 the opposite sides of the frame being

aligned to support crank shafts 10 consisting of webs 11 and crank pins 12. There are four crank shafts, two on the upper frame and two on the lower frame. They are arranged in pairs and each pair is adapted to support a paddle propeller such as shown at 6 or 7. The crank shafts 10 are provided with driving cranks 14 on their outer ends which are connected by driving links 15, said links being in turn driven by connecting rods 16, one on each side of the frame which may be actuated by a steam engine or driven from any other suitable source. The driving link 15 is extended at each end as at 17 to engage the pins 18 of the driving cranks 14. It can, therefore, be seen that all cranks will be driven in unison and at uniform speed by the connecting rods 16, and to insure a uniform drive it is obvious that the driving cranks 14 may be set at an angle of 90° with relation to each other, or otherwise positioned if desired.

As previously stated the crank shafts are positioned in pairs, the cranks of each pair being interspaced and superimposed as 80 shown in Figs. 1 and 2. Journalled on each pair of co-operating cranks are journal boxes 19 and connecting said boxes are rods 20. This arrangement insures a uniform movement of each pair of crank shafts and a uniform spacing between the same. The journal boxes 19 are provided for the support of arms 21, which in turn support the paddle blades 6 and 7. There are two arms arranged on each pair of aligned and superposed crank pins 12. The arms 21 are disposed at opposite ends of the respective crank pins and are connected and spaced apart by the blades 6 and 7 and cross braces of any suitable character. The arms 21 are 85 adapted to be raised and lowered with relation to the cranks and the journal boxes 19 and this is accomplished by hand wheels 22 and screw rods 23. There is one hand wheel and rod 23 for each arm 21. The arms 21 are arranged to straddle the journal boxes 19 and are guided thereby, each section of the arm 21 being channel-shaped to embrace the opposite faces of the journal boxes. They are raised and lowered with relation 90 to the journal boxes by the screws 23 and this is accomplished by connecting the upper ends of the arms by plates 24 which are threaded to receive the screw rods and adapted to function as nuts therefor, that 105

is the lower ends of the respective screw rods are connected with the upper journal boxes 19 and are turnable with relation thereto. Turning movement imparted to 5 any screw rod by means of the attached hand wheels 22 will therefore lift or raise the connected arms 21 with relation to the journal boxes and the dip of the blades 6 and 7 may accordingly be adjusted. This 10 is of extreme importance as it often happens that river steamers are heavily loaded and at other times are navigated with comparatively little freight. The hull proper is thus raised or lowered with relation to the 15 water line and the paddles would accordingly be raised and lowered, thus losing their maximum efficiency in either instance if their position was fixed. This is, however, obviated in the present instance as the paddle blades may be vertically adjusted at any 20 time so that their maximum work may be accomplished whether the ship is heavily or lightly loaded. For instance with a fixed paddle, whether it be of the stern wheel type, or the type here shown, either too 25 great or too small a dip would result under certain conditions. This would be exceedingly detrimental with the present arrangement as with a heavy load the blades would 30 have a tendency to back water during a portion of the stroke and thereby materially decrease the efficiency of the same.

In actual operation with a paddle propeller constructed as here shown it is possible to so adjust the blades 6 and 7 of the 35 paddles so that they will just clear the water when they are being lifted out by the cranks. They will therefore clear the water on the return stroke and will enter the water immediately when commencing the driving 40 stroke. Hence maximum efficiency may be obtained under all conditions.

While the structure here shown is more or less specific in design, I wish it understood 45 that changes in form and proportion may be resorted to within the scope of the appended claims, similarly that the materials and finish of the several parts employed may be such as the experience and judgment of 50 the manufacturer may dictate or varying conditions may demand.

Having thus described my invention, what I claim and desire to secure by Letters Patent is:—

55 1. A paddle propeller comprising a frame, two pair of superposed cranks journaled in the frame, each of said cranks comprising a pair of widely separated crank webs connected by a long crank pin, a pair 60 of interspaced vertically disposed arms connecting the crank pins and journaled thereon, a paddle blade secured to the lower ends 65 of the arms and connecting the arms, and a common connecting member for each end of the cranks to insure unitary movement of

the cranks, said connecting member comprising a straight bar with a T-shaped head formed on each end thereof and a connecting rod attached to the center portion of said member. 70

2. In a paddle propelling mechanism of the character described four crank shafts arranged in pairs, and one crank of each pair being disposed above the other, and means for insuring unitary rotation of said 75 cranks, said means comprising a bar having a T-shaped head on each end thereof, a pivotal connection between the T-shaped ends of the member and the respective cranks and a pivotal connection between the connecting rod and said member. 80

3. A paddle propeller comprising a frame, a pair of superposed cranks journaled in the frame, each of said cranks comprising a pair of widely separated crank 85 webs connected by a long crank pin, a pair of interspaced vertically disposed arms connecting the crank pins and journaled thereon, a paddle blade secured to the lower ends of the arms and connecting the arms, and 90 means permitting vertical adjustment of the arms and blades with relation to the crank pins. 95

4. A paddle propeller comprising a pair of superimposed cranks, a pair of arms supported by and journaled on the cranks, a paddle blade secured to the arms and connecting the same, and means for raising and lowering the arms, together with the blade, with relation to the cranks. 100

5. A paddle propeller comprising a pair of superimposed cranks, a pair of arms supported by and journaled on the cranks, a paddle blade secured to the arms and connecting the same, means for raising and 105 lowering the arms, together with the blade, with relation to the cranks, said means comprising journal boxes on the cranks, a sliding connection between the journal boxes and the arms, and a screw rod associated 110 with each arm, said screw rods being connected with the journal boxes and adapted to raise and lower the arms with relation thereto.

6. A paddle propeller comprising two 115 pair of superimposed cranks, means for driving said cranks in unison, a pair of arms carried by each pair of cranks, a paddle blade for each pair of arms and secured thereto, and means for raising and lowering 120 the arms, together with the paddle blade secured thereto, with relation to their respective cranks.

In testimony whereof I have hereunto set my hand in the presence of two subscribing 125 witnesses.
